UNITED STATES PATENT OFFICE.

GEORGE L. HARVEY, OF CHICAGO, ILLINOIS.

DRAW-GEAR FOR RAILWAY-CARS.

SPECIFICATION forming part of Letters Patent No. 447,323, dated March 3, 1891.

Application filed June 30, 1890. Serial No. 357,179. (No model.)

To all whom it may concern:

Be it known that I, GEORGE L. HARVEY, a citizen of the United States, residing at Chicago, Illinois, have invented certain new 5 and useful Improvements in Draw-Gears, of which the following is a specification.

My invention relates to certain improvements in draw-gear for cars, and has for its object to reduce the cost, weight, and number 10 of parts and to increase the strength and efficiency; and this object I accomplish by substituting for the usual draft-sills flat metal plates, which are forged, pressed, or cast to provide marginal strengthening-flanges, and 15 have their webs offset to provide a pocket for the follower-blocks, between which the buffer-springs are confined and to which the shank of the draw-head is secured. These plates are reduced toward their forward ends to provide 20 a shoulder which abuts against the inside of the end sill and a neck which projects beyond the end sill and is upturned to engage its front side, whereby the shocks both in pulling and buffing are transmitted to the 25 end sill.

My improvements are adapted to be used in connection with the standard spring-pocket and draw-head construction, and therefore do not necessitate a reconstruction of these parts.

30 In the accompanying drawings, Figure 1 is a side elevation of my improved draw-gear, the end sill being shown in cross-section and one of the longitudinal sills in side elevation, partly broken away. Fig. 2 is a plan view of 35 the same parts; Fig. 3, a vertical section through the center of the draw-gear. Fig. 4 is a perspective view of one of the draft-plates detached, and Fig. 5 is an elevation and section on the line 5 5 of Fig. 2.

40 In the drawings I have illustrated portions of a frame whose longitudinal body-sills are metal U-beams, each sill consisting of two members A A', and whose end sills each consist of two members B B', said members being slightly separated.

C represents the floor, D the dead-wood, and E the draw-bar, which, as shown, has the Janney form of head and a round shank. To the rear end of this shank is applied the usual 50 follower-blocks F F' and the spring G, and the follower-blocks and spring are inclosed

by the usual strap H. The difficulty encountered heretofore has been to so mount or attach these parts as to prevent their being knocked out by the shocks of coupling and buffing, and to remedy these defects is the principal object of my invention. This I do by providing a draft-connection which takes its bearings directly upon the end sill of the car and which comprises in the preferred 60 form of construction two metal plates which have integrally formed therewith angular marginal flanges to impart strength, an offset portion to provide a pocket or bearings for the follower-blocks, and a reduced portion 65 to form a shoulder to abut against the inner side of the end sill, and a neck which projects beneath the sill and having a hooked outer end to engage the frontside of the end sill of the car. These plates are adapted to be bolted or otherwise secured to the longitudinal sills, the bolts having no work to perform except to sustain the weight of the plates, while the shocks are sustained by the end sill. The form of these plates is shown in Fig. 4 of the 70 drawings. Each has a web or body portion I, with a right-angled marginal flange i, and an offset portion I', pressed out to provide a pocket to receive and furnish bearings for the follower-blocks. The front end of this plate 75 is reduced or drawn down to form a shoulder I'', which takes a bearing on the inner side of the end sill, and a neck J, which is adapted to pass beneath the end sill and is turned up at the outer end to furnish a shoulder j, which takes a bearing on the front side of the end sill. The web of the plate may be perforated for the passage of bolts or rivets K, by which it is secured to the members of the longitudinal sill, and its top flange may also be apertured for the securing of the strap L, having a hooked end l, and which strap projects over the top of the end sill and its hook is engaged with the upper front edge thereof, the tie-bolt M securing said strap with the neck 80 90 J of the plate, and thus securely anchoring the draft-plate to the end sills and distributing the strain thereon. The flange at the bottom of the plate and at the sides of the pocket may be apertured for the securing thereof with of a flat strap N, which forms a support or way on which the follower-blocks slide. 100

To decrease the weight and at the same time impart additional strength to the draft-plates, I prefer to arch them, as at O in the drawings, the legs of the arch springing from the lower corners of the pockets. It will be understood that two of these plates are employed, being secured each to one of the longitudinal sill members and separated sufficiently for the reception of the spring-pocket.

10 The utility of this construction arises chiefly from the employment of a draft-connection which has integral portions engaged directly with the end sill, so that the strains and shocks of service are transmitted to the end sill instead of mediately through fastening-bolts.

I do not of course limit my invention to the precise form of draft-plate herein shown, as structural changes may be made therein without departing from the spirit and scope of my invention, the gist of which resides in such a construction of the draft-plate as enables its direct engagement with the end sill and provides also an integrally-formed bearing for the ends of the follower-blocks.

25 I claim—

1. In a draw-gear, a draft-connection comprising flanged plates secured to the sides of the longitudinal sill or sills of the car, and having an offset portion projected below said sills to provide a pocket to receive the follower-blocks and connected parts, substantially as described.

2. In a draw-gear, a draft-connection comprising plates, each having a bearing on the end sill and on the vertical sides of the longitudinal sill or sills, an extension adapted to project beyond the end sill and engage the front thereof, and an offset portion to furnish

bearings for the follower-blocks, substantially as described.

3. In a draw-gear, a draft-connection comprising two metallic plates, each having a web portion and strengthening-flanges, a shoulder to engage the inner side of the end sill, a reduced portion to project beneath the end sill and upturned to engage the front thereof, and an offset portion in the web to provide bearings for the follower-blocks, substantially as described.

4. In a draw-gear, a draft-connection comprising two draft-plates, each consisting of a web with marginal strengthening-flanges, a reduced extension thereof to project beneath the end sill and upturned to engage the same, a strap secured to the top of the plate and hooked for engagement with the end sill, and an offset portion in the web to provide bearings for the follower-blocks, substantially as described.

5. In a draw-gear, a draft-connection comprising two draft-plates, each consisting of a web with marginal strengthening-flanges, a reduced extension thereof to project beneath the end sill and upturned to engage the same, a strap secured to the top of the plate and hooked also for engagement with the end sill, and an offset portion in the web to provide bearings for the follower-blocks, said offset portion having its lower edge arched and a strap connecting the lower points of the arch to provide a way whereon the follower-blocks slide, substantially as described.

GEORGE L. HARVEY.
